WILLIAM T. BENJAMIN, OF NEWARK, NEW JERSEY, ASSIGNOR TO UNITED SHOE MACHINERY COMPANY, OF PATERSON, NEW JERSEY, A CORPORATION OF NEW JERSEY.

LAP-SEAMING MECHANISM.

1,238,857.

Specification of Letters Patent. Patented Sept. 4, 1917.

Application filed April 24, 1916. Serial No. 93,162.

To all whom it may concern:

Be it known that I, WILLIAM T. BENJAMIN, a citizen of the United States, residing at Newark, in the county of Essex and State of New Jersey, have invented certain Improvements in Lap-Seaming Mechanisms, of which the following description, in connection with the accompanying drawings, is a specification, like reference characters on 10 the drawings indicating like parts in the several figures.

My invention relates to lap seaming mechanism for uniting overlapped ends by a line of stitches, and more particularly to stitching mechanism in combination with certain novel work guiding means constructed and arranged to unite the overlapped ends of separate pieces of material with their edges in parallelism by one or more lines of stitches 15 extending longitudinally of the overlap between the parallel edges. The invention provides means which may be advantageously employed to so unite the overlapped ends without reference to the initial shape 20 of the edges of such ends and, additionally, to so unite the ends by one or more lines of stitches forming a straight seam and giving a neat appearance to the work. Such a construction is used to particular advantage in 25 uniting overlapped ends having convex edges so that the parts are convexed longitudinally of the overlapped ends with the edges themselves in parallelism.

Such an overlap may be advantageously 30 employed in the so-called "heel-seaming" of the counter portion of shoe uppers. The rear ends of two opposite side pieces of the counter are formed to overlap at the rear of the counter substantially at the longitudinal 35 median line of the counter and are joined by lap seaming permanently to convex the overlapped portions longitudinally of the edges and vertically of the counter so that they will closely conform to the vertical contour 40 of the rear end face of the last heel and of the heel of the foot.

This method of forming the counter portion of shoe uppers is disclosed in an application filed March 24, 1916, by Thomas 45 F. Whelan, Serial No. 86,417, for shoes and the method of making the same, and is characterized by the use of two side pieces forming the counter portion of the upper having their rear ends extended beyond the longi-

tudinal median line of the counter to overlap and formed with convex rear edges which are stitched together in parallelism, the curvature of the edges being somewhat greater than the vertical curvature of the rear end face of the heel of the last to provide fullness to enable the overlap to conform to the horizontal curvature of the heel under lasting tension, the connection of the overlapped ends with their convex edges in parallelism necessarily causing the ends to 55 be convexed longitudinally of the line of overlap and vertically of the counter.

While my invention is particularly adapted for use in connection with the described method of joining and forming the rear 60 ends of the counter portions of shoe uppers and is illustrated and described in connection with this method, in its broad aspect it is useful generally for lap seaming and more especially for uniting overlapped ends with 65 their edges in parallelism.

In one aspect the invention consists in the combination of a suitable stitching mechanism, spaced work edge guides and means arranged to support separate pieces of work 70 with their ends overlapped to coöperate with said guides.

A feature of the invention consists in laterally spaced work edge guides having parallel guiding surfaces positioned in different horizontal planes, and work supporting means arranged to position separate pieces of material in the respective horizontal planes of said guiding surfaces. Such a construction enables the ends of the separate pieces to be overlapped to lie in parallel horizontal planes and substantially in contact at the stitching points. The coöperation of the work supports and work edge guides as to plane alinement permits the 75 amount of overlap of the ends and the parallelism of the edges to be accurately gaged and maintained.

Another and important feature of the invention consists in combination with the 80 work supporting and edge guiding means mentioned above, of means to hold down the edge of the stock as it is fed and guided to the stitching point. When two ends with 85 convex edges are stitched together in overlapped relation with their edges in parallelism, one or both of the plies must be 90 "sprung" into a curve to place their edges 95

in parallelism. This crimping operation tends to cause the edges to pucker, and means acting to hold the edge of the stock will prevent puckering and is therefore decidedly advantageous under these and similar conditions.

A further feature of the invention consists in the combination of laterally spaced work edge guides having parallel guiding surfaces positioned in different horizontal planes, with work supporting means arranged to support separate pieces of work with their ends overlapped to extend into the respective horizontal planes of said guiding surfaces, and a stitching mechanism having two laterally spaced needles and including means to guide said needles to engage the work at points between the guiding lines of the laterally spaced work edge guides. By positioning the needles to stitch the overlap between the parallel guiding surfaces, the line of stitching may be arranged to extend along and closely adjacent to each edge of the work so that not only are the overlapped portions securely stitched together but a neat seam is provided, extending parallel with the exposed edge and forming a straight seam.

A related feature of the invention consists, in the combination recited, of a work support having a guiding face concaved laterally of the edge guiding surfaces and extending into the horizontal plane of the uppermost of said guiding surfaces. A work support of this character enables the work to be easily guided toward and against the coöperating edge guiding surface and facilitates the feeding of the work to the machine.

A still further feature of the invention consists in the combination of a stationary work support, a presser foot vertically movable toward and from said support, having one or more needle guides and having at one side a work edge guiding surface, a guide member having a second work edge guiding surface laterally spaced from and parallel to the first edge guiding surface and in a horizontal plane to engage the edge of work on said stationary support, and having a work supporting face extending in the horizontal plane of the edge guiding surface of the presser foot in the lowered position of the presser foot.

This combination of parts is particularly advantageous in that it enables the work to be positioned upon the stationary support with one edge in engagement with the coöperating guiding surface, and with the edge of the coöperating piece of work positioned on the supporting face of the guide member in the horizontal plane of the guiding surface of the presser foot in the lowered position of the presser foot. This arrangement enables the work to be readily assem-

bled in coöperative relation to the guiding surfaces, and in actual practice effects substantial saving in time.

These and other features and advantages will be more fully apparent from the following detailed description when read in connection with the accompanying drawings illustrating one and a preferable embodiment of the invention.

In the drawings:

Figure 1 is a plan view of lap seaming mechanism constructed in accordance with the present invention, only such parts of the stitching mechanism being shown as are essential to an understanding of the invention;

Fig. 2 is a vertical sectional view on the line 2—2, of Fig. 1, with the throat plate, guide member and presser foot in position to receive the work;

Fig. 3 is a similar vertical sectional view with the parts in work guiding and engaging position;

Fig. 4 is an end elevation of the guide member carried by the throat plate;

Fig. 5 is a longitudinal section through the presser foot on the line 5—5 of Fig. 2;

Fig. 6 is an inverted perspective of the rear of a shoe counter having the overlapping ends of its two side pieces stitched together in overlapped position and convexly shaped by the use of the lap seaming mechanism of this invention.

The usual top or work plate 4 of a sewing machine or "stitcher" is mounted upon the face of the frame or table 2 and carries a throat plate 6 having the usual slot therein through which the feed dog 8 extends to engage and feed the material through the stitching mechanism. A presser foot 10 is suitably mounted for vertical movement toward and from the throat plate 6 which constitutes a stationary support for work. This presser foot is formed with two laterally spaced needle guiding apertures 12 through which needles 14 (Fig. 1) may extend and operate in the usual manner. Preferably the feed dog is shaped to engage the under ply of the work between the needles as shown in Fig. 1.

At one side, the base of the presser foot is formed with a longitudinally extending rib 18 forming a guiding wall or surface. This guiding wall is extended forwardly beyond the forward extremity of the presser foot as a finger 16 and serves to hold down the face of the work as it approaches the stitching point. (See Figs. 1 and 3.)

At one side of the presser foot, a spring plate or arm 20 is secured at one end to the throat plate or other suitable stationary support and extends in the direction of the presser foot and is attached to and supports a guide member 22 normally to extend slightly above the surface of the throat

plate. This guide member is formed with a rib 24 extending longitudinally thereof at its under face and forming a work edge guiding surface 26 parallel with the work edge guiding surface 18 of the presser foot but located in lower horizontal plane when the presser foot is in its lowered position (see Fig. 3). The edge of the guide member 22 adjacent to and forwardly of the 5 presser foot and intermediate of its ends, is formed with an offset flange 28 overhanging the work edge guiding surface 26 and extending to a point beneath the forward edge of the presser foot.

10 The upper portion of the guide member is provided with a concaved work supporting surface 30 inclining downwardly from its front end in the direction of the stitching point as is indicated at 32, Fig. 4, the concaved portion extending across the flange 28 so that the work may be "sprung" into alignment with the finger with the edge of the flange constituting the end of the "sprung" curve and terminating, longitudinally, adjacent to the point where the needle 15 enters the work piece which it guides.

The two separate pieces of material whose edges are to be overlapped and stitched together are designed to be supported adjacent 20 to the stitching point by the throat plate 6 and by the surface of the guide member 22 indicated at 28 and 30. With separate pieces of work positioned in overlapped relation upon the supporting surfaces, the presser foot 10 may be lowered to engage the upper 25 surface of the piece of work supported by the guide member 22. Inasmuch as the flange 28 of the guide member is in the line of movement of the presser foot, the latter 30 will be pressed downwardly, its rib 24, which normally projects partly into an alined slot in the throat plate and table, being pressed farther into the slot and its work supporting surface 28, 30 being lowered into 35 the horizontal plane of the work edge guiding surface 18 of the presser foot. It will be obvious that the piece of work supported by the guide member 22 will be positioned so that its edge at one end will engage the guiding surface 18 of the presser foot. The other 40 piece of work will be positioned upon the throat plate 6 with its end extending beneath and overlapped by the end of the first piece of material and with its edge engaged with the edge guiding surface 26 of the 45 guide member, the flange 28 of said member operating as a hold down lip and maintaining the second piece of material in a substantially flat position against the throat plate and against the feed dog. The spring arm 20 supporting this guide member normally elevates it above the throat plate sufficiently to allow a ply of material of maximum thickness to be inserted against its 50 guiding edge 26 and below its hold-down flange 28. The presser foot will engage the surface of the first or upper ply of material and hold it downward in contact with the lower ply of material at the stitching point, the feed dog engaging the under face of the 55 lower ply at this point. The presser foot will also act to force down the guide member 22 to maintain the lower ply substantially flat but not so that the guide member 60 clamps the edge of the lower ply. The overhanging flange 28 of the guide member serves to hold down the marginal portion of the lower ply and prevents puckering at the thin skived edge of the ply as the latter is turned and fed. It is to be noted, also, that 65 this flange, in coöperation with the edge gage surface 26, maintains the "spring" of the lower ply up to the stitching point. The two plies are separately held down adjacent to the stitching line, and each is free to turn 70 on the stitching line or hold down line at every instant, so that in the feeding operation, the stock may be turned or "walked around curves" to bring the edges in parallelism at the stitching point. 75

In the drawings, in order to illustrate the operation of the described mechanism, I have shown two separate pieces of material A and B, forming the two side pieces of the counter portion of a shoe upper whose rear 80 ends are to be overlapped and stitched together. The two side pieces A and B are provided with convex rear edges. These pieces will be initially positioned preparatory to stitching by placing the upper piece 85 A to position one end, say the upper end, adjacent to the line of the needles 14, the body of the side piece A being "sprung" into the concavity of the supporting surfaces 28, 30 so that its edge may engage the guiding wall 90 95 100 105 110 115 120 125 130

18 of the presser foot and extend in parallelism with the edge of the side piece B when the presser foot is lowered. The lower side piece B is inserted at approximately the same time to extend its upper end beneath the forward portion of the presser foot with its convex edge moved into engagement with the work edge guiding surface 26. The presser foot 10 is now lowered and the upper work piece and the upper and lower side pieces are adjusted by hand to engage their upper ends with their respective and parallel work edge guiding surfaces 18 and 26. The stitching mechanism is then operated, the overlapped ends of the two side pieces A and B being progressively fed toward the needles 14, the operator manipulating the side pieces by hand to maintain the edges in engagement with the guiding surfaces 18 and 26 as the material approaches the stitching point. The upper ply A is "sprung" into the concavity of the supporting surface 28, 30, the flange 28 serving to extend this surface to a point closely adjacent to the needle. The needles 14 are positioned to engage the

material at points closely adjacent to but within the respective edges of the overlapped ends, so that as the overlapped ends are fed through the machine, two lines of 5 stitches will be inserted closely adjacent to the edges and parallel to the edges and to each other. The work edge guiding surfaces extend in front and in the rear of the needle guides and insure the parallelism of the 10 edges of the upper and lower plies as they are stitched together.

The work contacting face of the guide member 22, provides a guide for the finger of the operator in feeding the side piece to 15 the stitching point, the inclined surface 32 bringing the overlapping portions of the two side pieces progressively in closer relation as the pieces are fed toward the stitching point. Additionally, since the oppositely convexed 20 edges of the side pieces A and B are held in parallelism while being stitched, the laterally concaved surface 30 of the guide member permits the side piece A to be turned or bowed out of the plane of the other side 25 piece B in compensation for the bending of the overlapped ends of the material of the side pieces to position and maintain their convex edges in parallelism.

In lap seaming two separate pieces having 30 convex edges which are stitched together in parallelism, it will be necessary to convex the overlapped portions longitudinally of their line of overlap, and, in the present instance, vertically of the shoe counter, in order to secure the parallel alinement of the convex 35 edges. Lap seaming two side pieces forming the counter portion of a shoe upper in the manner described provides the side pieces with a convexity extending in the line 40 of their junction and vertically of the counter as illustrated in Fig. 6, and in addition, effects this result by parallel lines of stitches which form a straight upright back seam and afford a very neat appearance at 45 the line of junction of the parts.

While my invention is herein described and illustrated as particularly adapted for work of this character, it must be understood that the construction of the lap seaming mechanism is independent of any particular 50 shape of overlapping ends and is independent of the particular use or art to which the overlapping pieces may be applied. In the appended claims, therefore, it is not intended that the invention be construed as limited to use in uniting the overlapped ends 55 of shoe parts, such as described.

Having thus described my invention, what I claim as new and desire to secure by Letters Patent of the United States is:—

1. A lap seaming mechanism having, in combination, a stitching mechanism, a presser foot and a coöperating member constructed to present spaced work edge guides 65 arranged to guide the edges of overlapped

pieces of work along parallel lines, and means to support separate pieces of work with their edges overlapped to coöperate with said guides.

2. A lap seaming mechanism having, in 70 combination, a stitching mechanism, laterally opposed work edge guides having parallel guiding surfaces positioned in different horizontal planes and arranged to guide overlapped plies of work to the stitching 75 mechanism with their overlapping edges in parallelism, means to support the plies in overlapped relation, with their overlapped edges in the horizontal planes of their edge guides, and means bodily yieldable upwardly 80 from the lower ply, arranged and operative to maintain the overlapped edge of said lower ply in flat condition as it is fed to the stitching mechanism.

3. A lap seaming mechanism having, in 85 combination, a stitching mechanism, laterally opposed work edge guides having parallel guiding surfaces positioned in different horizontal planes and arranged to guide the edges of overlapped plies of work to the 90 stitching mechanism with said overlapping edges in parallelism, and work supporting means arranged to support upper and lower plies in overlapped relation with their overlapping edges in the horizontal planes of 95 their edge guides, the supporting means for the upper ply being constructed and arranged to overlie and maintain in flat condition the overlapped edge of the lower ply.

4. A lap seaming mechanism having, in 100 combination, a stitching mechanism, laterally spaced work edge guides having parallel guiding surfaces positioned in different horizontal planes and arranged to guide the edges of overlapped plies of work to the 105 stitching mechanism with said overlapping edges in parallelism, means to support upper and lower plies in overlapped relation with their overlapping edges in the horizontal planes of their respective edge guides and 110 to maintain the overlapped edge of the lower ply in flat condition as it is fed to the stitching mechanism, the support for the upper ply having a supporting surface inclined to enable the operator to position the overlapping edge of the upper ply in the horizontal plane of its edge guide as it is fed to the stitching mechanism.

5. A lap seaming mechanism having, in 115 combination, a stitching mechanism, laterally spaced work edge guides having parallel guiding surfaces positioned in different horizontal planes, and work supporting means to position separate pieces of material with their edges overlapped and in the respective horizontal planes of said guiding surfaces and with the body portions of the upper piece of material adjacent to its edge inclined downwardly toward the plane of its edge guide.

6. A lap seaming mechanism having, in combination, a presser foot and a coöperating member constructed to present work edge guiding surfaces positioned in different horizontal planes, work supporting means arranged to support separate pieces of work with their edges overlapped to extend into the respective horizontal planes of said guiding surfaces, and a stitching mechanism having a needle and including means to guide said needle to engage the work at a point between the guiding lines of the laterally spaced work edge guides.

7. A lap seaming mechanism having, in combination, laterally spaced work edge guides having parallel guiding surfaces positioned in different horizontal planes, two work supporting members arranged to support separate pieces of work with their edges overlapped to extend into the respective horizontal planes of said guiding surfaces, one of said work supports having a guiding face concaved laterally of the edge guiding surfaces and extending into the horizontal plane of one of said surfaces, and a stitching mechanism having laterally spaced needles and including means to guide said needles to engage the work at points between the guiding lines of the laterally spaced work edge guides.

8. A lap seaming mechanism having, in combination, laterally spaced work edge guides having parallel guiding surfaces positioned in different horizontal planes, work supporting means arranged to support separate pieces of work with their edges overlapped to extend into the respective horizontal planes of said guiding surfaces, and a stitching mechanism having two laterally spaced needles and including means to guide said needles to engage the work at points between and adjacent to the guiding lines of the laterally spaced work edge guides to unite the overlapped ends of the work by lines of stitches extending along and adjacent to their edges.

9. A lap seaming mechanism having, in combination, laterally spaced work edge guides having parallel guiding surfaces positioned in different horizontal planes, two work supports arranged to support separate pieces of work with their edges overlapped to extend into the horizontal planes of said guiding surfaces to engage said surfaces, and including a work support having a contact surface concaved laterally of and into the plane of the uppermost guiding surface, and inclining downwardly toward the stitching point, and stitching mechanism having a needle with means to guide said needle to engage the work at a point between the guiding lines of the laterally spaced work edge guides.

10. A lap seaming mechanism having, in combination, a stationary work support, a

presser foot vertically movable toward and from said support and provided with a needle guide and having at one side a work edge guiding surface, and a guide member having a second work edge guiding surface laterally spaced from and parallel with the first edge guiding surface and in a horizontal plane to engage the edge of work positioned on said stationary support and having a work supporting face in the horizontal plane of the edge guiding surface of the presser foot in the lowered position of the presser foot.

11. A lap seaming mechanism having, in combination, a stationary work support, a work feeding dog, a stitching mechanism including a presser foot vertically movable toward and from said support and feeding dog and having laterally spaced needle guides and a work edge guiding surface on one side of the presser foot, a guide member having a second work edge guiding surface laterally spaced from and parallel to the first edge guiding surface and in a different horizontal plane to engage the edge of work positioned on said stationary support and extending beneath and transversely of the presser foot and itself having a work supporting face inclining downwardly transversely of the presser foot and into the horizontal plane of the edge guiding surface of the presser foot in the lowered operative position of the presser foot.

12. A lap seaming mechanism having, in combination, a stationary work support, a stitching mechanism including a feeding dog, and a presser foot vertically movable toward and from said support and feeding dog provided with laterally spaced needle guides and having a work edge guiding surface on one side of the presser foot and spaced laterally from the needle guides, a guide member stationary relatively to the presser foot provided with a second work edge guiding surface laterally spaced from and parallel to the first edge guiding surface and in a horizontal plane to engage the edge of work positioned on said stationary support and extending transversely beneath the presser foot and itself having a work supporting face concaved laterally of the edge guiding surface and extending transversely of and beneath the presser foot into the horizontal plane of the edge guiding surface of the presser foot in the lowered operative position of the presser foot.

13. A lap seaming mechanism having, in combination, a table, a work guide having a lateral face to guide an edge of the lower ply of the work and a flange to overlie said ply of the work adjacent to said edge, and a presser member having a lateral face to guide an edge of the upper ply of the work and a portion to overlie the upper ply of

the work between its edge and the lateral face of the said work guide.

14. A lap seaming mechanism having, in combination, a table having a recess in its face, a presser foot, and a depressible arm overlying the table and having a downward projection located over said recess and presenting a lateral face adapted to guide the edge of the lower ply of the work and having a flange which is adapted to extend between the said lower ply and an upper ply and beneath the presser foot to cause the arm to be depressed by the presser foot.

15. A lap seaming mechanism having, in combination, a table, a presser foot having a needle guide and presenting for engagement with an upper ply of the work a lateral edge-guiding face extending a substantial distance in front and in the rear of the needle guide, and a depressible arm overlying the table and presenting for engagement with the lower ply of the work a lateral edge-guiding face which also extends in front and in rear of the needle guide and is parallel 25 with the edge-guiding face on the presser foot.

16. A lap seaming mechanism having, in combination, a table, a presser foot and a depressible arm presenting a lateral edge guiding face for the lower ply of the work and a flange positioned beneath the presser foot and adapted to overlie and hold down the margin of the lower ply of the work.

17. A lap seaming mechanism having, in combination, a table having a recess, a presser foot, and a depressible arm having a flange extending under the presser foot between the lower and upper plies of the work for engagement by the presser foot when

lowered and having also a downward projection beneath and laterally offset from the flange and presenting an edge guide for the lower ply of the work and normally extending into said recess and movable farther into the recess as the arm is depressed, by the 45 presser foot.

18. A lap seaming mechanism having, in combination, a table, a presser foot having a needle guide, and a work guide presenting an edge-guiding face for the lower ply of the 50 work and a flange arranged to project over the work and terminating at its rear edge under the presser foot and in front of the needle guide.

19. A lap seaming mechanism having, in 55 combination, a table, a presser foot having a needle guide, and a work guide presenting an edge-guiding face for the lower ply of the work both in front of and in rear of the needle guide, said work guide having also a 60 flange located wholly in front of the needle guide and overlying the lower ply of the work.

20. A lap seaming mechanism having, in combination, a table, a work guide having a 65 lateral face to guide an edge of the lower ply of the work and a flange to overlie and hold down said ply adjacent to said edge, and a presser member having a lateral face in parallelism with the lateral face of said guide 70 arranged to guide an edge of the upper ply of the work and having a portion to overlie and hold down the upper ply of the work between its guided edge and the lateral face of the work guide.

In testimony whereof I have signed my name to this specification.

WILLIAM T. BENJAMIN.
